(57) **CLAIM**

The ornamental design for a tape dispenser, as shown and described.

DESCRIPTION

FIG. 1 top, front, and right side perspective view of a tape dispenser showing my new design;

FIG. 2 a top, rear, and left side perspective view thereof;

FIG. 3 is a front elevational view thereof;

FIG. 4 is a rear elevational view thereof;

FIG. 5 is a left side elevational view thereof, the right side being a mirror image of that shown;

FIG. 6 is a top plan view thereof;

FIG. 7 is a bottom plan view thereof; and,

FIG. 8 is an additional top, front, and right side perspective view thereof.

The broken-line disclosure of rolls of tape in the views are for illustrative purposes only and form no part of the claimed design.
